CLAIM

We claim the ornamental design for the snap-fit measuring spoon, as shown and described.

DESCRIPTION

FIG. 1 is a perspective view of a snap-fit measuring spoon, showing our new design;

FIG. 2 is a top view of the snap-fit measuring spoon;

FIG. 3 is a left side view of the snap-fit measuring spoon, the right side view being a mirror image;

FIG. 4 is a bottom view of the snap-fit measuring spoon;

FIG. 5 is a front view of the snap-fit measuring spoon; and,

FIG. 6 is a back view of the snap-fit measuring spoon.
